WILSON E. PORTER, OF NEW HAVEN, CONNECTICUT, ASSIGNOR TO THE NEW HAVEN CLOCK CO., OF NEW HAVEN, CONNECTICUT, A CORPORATION.

TIMING DEVICE FOR THE BALANCE-WHEEL UNITS OF CLOCK AND WATCH MOVEMENTS.

Application filed September 22, 1926. Serial No. 136,976.

My invention relates to an improved device for timing or vibrating the balance-wheel units of clocks and watches, preparatory to their ultimate assemblage in the movements for which they are designed, the object of my present invention being to produce a simple, compact, time-and-labor saving device of superior convenience and effectiveness.

With these ends in view, my invention consists in a timing or vibrating device for the balance-wheel units of clocks and watches, characterized by a pair of yielding impulse-fingers positioned between the master and the trial units installed in the device so as to engage sharply with the edges of the rims of their balance-wheels and simultaneously start the same vibrating in opposite directions.

My invention further consists in a timing or vibrating device characterized as above and provided with indicating pointers having their ends in opposition and respectively vibrated by the master and trial units and reflected in a mirror located back of them, so as to present their images to the eyes of the timer.

My invention further consists in a timing or vibrating device characterized as described and having certain other details of construction as will be hereinafter described and pointed out in the claims.

In the accompanying drawings:

Fig. 1 is a broken plan view of a timing device constructed in accordance with my invention;

Fig. 2 is a view thereof in front elevation, with a portion of the front frame-plate broken away;

Fig. 3 is a view thereof in right-hand side elevation;

Fig. 4 is a broken view in horizontal section on the line 4—4 of Fig. 2; and

Fig. 5 is a detached broken plan view of the retaining-stud provided for anchoring the upstanding free end of the balance-spring of the trial-unit.

In carrying out my invention, as herein shown, I employ a front frame-plate 10, an

intermediate frame-plate 11 and a back 50 frame-plate 12, these plates being united at their corners by pillars 13 and secured to a base 14. A horizontally-arranged operating-lever 15, provided with a ball-handle 16 at its projecting outer end, is hung upon a 55 rock-shaft 17 journaled in the plates 10 and 11. At its inner end this lever is connected by a screw-stud 18 with a horizontally-arranged lifting-block 19 normally resting upon a stop-screw 20 in the plate 12. At 60 its respective ends, the said block 19 carries two corresponding vertically-arranged lifting-rods 21 adjustably secured to it by screws 22 and vertically movable in guide-lugs 23 offsetting from the front of the intermediate frame-plate 10. The projecting upper ends of these rods 21 enter a horizontally-arranged finger-carrying block 24 to which they are respectively secured by screws 25. The upper face of the block 24 70 mounts two corresponding oppositely-inclined yielding flat impulse-fingers 26 and 27 secured in place by screws 28. An operating-spring 29, attached at its lower end to a stud 30, has its upper end attached to a 75 stud 31 depending from the center of the lower face of the lifting-block 19 and exerts a constant effort to maintain the same in engagement with the stop-screw 20, whereby the block 24 and the fingers 26 and 27 are 80 normally maintained in their depressed or retired positions. An adjusting-screw 32, mounted in the block 19 and secured therein by a set-screw 33, engages at its upper end with a stop-lug 34 mounted in the plate 11 85 to limit the upward movement of the inner end of the operating-lever 15 and hence the upward thrust of the yielding impulse-fingers 26 and 27. A hole 35 in the inner end of the lever 15 provides clearance for the 90 screw 33 and also for access thereto.

The impulse-finger 26, which has its upper end very slightly curved outward, extends at a right angle under the rim of the balance-wheel 36 of the master-balance 95 wheel-unit, which also comprises a staff 37 and a balance-spring 38, while the impulse-finger 27 is similarly outwardly curved and

extends at a right angle under the rim of the balance-wheel 39 of the balance-wheel trial-unit, which also comprises a staff 40 and a balance-spring 41.

5 It will be noted, by reference to Fig. 2, that the impulse-finger carrying-block 24 is positioned centrally below the master balance-wheel and trial-balance wheel units, so that when the block is raised by striking a 10 smart blow upon the operating-lever 15, the impulse-fingers 26 and 27 will be sharply engaged with the edges of the rims of the balance-wheels 36 and 39 respectively, and start the same rotating in opposite directions with an impulse sufficient for their adequate comparison.

The master balance-wheel unit, it will be understood, has previously been regulated and hence the operating length of its spring 20 predetermined and secured by a pin 42 in a stud 43 in a rocking-lever 44 mounted upon the forward end of a rock-shaft 45 rocking in centers 46 and 47 in the plates 10 and 12 respectively, the rocking movement of the 25 lever 44 being limited by a stop-pin 48 carried by it and located between a pair of stop-pins 49 projecting inwardly from the plate 10. At its inner end, the shaft 45 carries an inwardly-extending horizontally-arranged index-pointer 50, which is located in the space between the plates 11 and 12. A similar pointer 51 is secured to the inner 30 end of a rock-shaft 52 mounted in centers 53 and 54, corresponding to the centers 47 and 46, and mounted in the plates 10 and 12. The two pointers, as thus arranged, are in line with their ends, close together but not touching. They participate in the vibrations of the respective balance-wheel 35 units and will vibrate in real unison only when the two units are in unison. They will, indeed, start in unison but depart therefrom as the units vibrate, to a degree dependent upon the departure of the spring 40 41 from correct length.

At its forward end, the shaft 52 carries a rock-lever 55, limited in movement by a stop-pin 56 carried by it and located between a pair of stop-pins 57 projecting inwardly from the plate 10. At its inner end, the lever 55 carries an inwardly-projecting stud 58 having, in its outer edge, a vertical notch 59 (Fig. 5) receiving the up-standing free outer end of the balance-spring 41 of the trial-unit, the said end of the spring 41 being normally held in place in the said notch 59, but vertically movable therein, by the tension of a spring-arm 60 up-standing from a spring 61 encircling the rock-shaft 52.

65 A clearance-cut 62 in the upper edge of the plate 12, midway the length thereof, exposes the rear faces of the index-pointers 50 and 51 for the reflection of their inner ends in close opposition, as shown in Fig. 1, in

a swinging mirror 63 mounted in a post 64 upstanding in the base 14, near the rear edge thereof. By preference, the rear faces of the said pointers will be covered with white enamel, so as to heighten their visibility in the mirror and, for the sake of contrast, it is desirable to have the rear faces of the plates 11 and 12 black, so as to further heighten the visibility of the pointers. Preferably, also, the front face of the intermediate plate will be covered with white enamel, so as to increase the visibility of the master and trial balance-wheel units and their delicate hair-springs.

70 In using my improved device, a carefully-pre-regulated balance-wheel unit is installed in the device in the screw-pivot bearings 65 and 66 mounted in the frame-plates 10 and 11 respectively, to the left of the centers thereof, as shown in Fig. 1. This balance-wheel now becomes the master balance-wheel and remains a fixture in the device for the timing of balance-wheel units like it.

75 The trial balance-wheel is now installed in the screw-pivot bearings 67 and 68, the latter being furnished, for convenience of operation, with a knurled finger-button 69, and stabilized in its position by a helical spring 70.

80 A sharp downward blow by the "timer,"—i. e., the person using the device,—on the projecting end of the operating-lever 15, overcomes the tension of the spring 29 and drives the edges of the impulse-fingers 26 and 27 sharply against the edges of the rims of the balance-wheels 36 and 39 of the master and trial balance-wheel units, whereby they are simultaneously given an impulse in opposite directions, that is, the wheel 39 in a clockwise direction, and the wheel 36 in a counter-clockwise direction, so that thereafter they will continue vibrating in opposite directions under the power thus devolved upon their balance-springs. Inasmuch as the ends of the impulse-fingers 26 and 27 85 bite directly into the rims of the balance-wheels and as the leverage represented by the diameters of these wheels is considerable, the power transmitted to them will be adequate for all purposes of comparing the adjustment of their balance-springs. Also, they will be started simultaneously, whereas, in the timing devices of the prior art, the starting of the two units by wiping their respective staffs cannot be depended upon to start the units simultaneously.

90 It will be understood, of course, that the instant after the blow of the finger of the "timer" has been delivered upon the lever 15, the spring 29 will act to restore the lever 15 to its normal position and so clear the ends of the yielding impulse-fingers 26 and 27 from the rims of the respective balance-wheels almost instantly, leaving them free to "vibrate," as the term is.

The vibration of the index-pointers 50 and 51 participates in the vibration of the two units and provides a means for their comparison, which is noted by the "timer" in the mirror 63. The two pointers will start together, but the pointer 51 of the trial-unit will soon either move ahead or lag behind the pointer 50 of the master-unit, dependent upon the length and strength of the balance-spring 41, as compared with the balance-spring 38 of the master balance-wheel unit.

The user of the device, noting the behaviour of the pointers 50 and 51 in the mirror 63, now releases the free end of the balance-spring 41 by manually springing back the spring-arm 60, after which he will raise or lower the upstanding free end of the spring 41 in the slot 59 to increase or decrease the length of the said spring as is, in his judgment, required to conform its action to the action of the balance-wheel spring 38.

The above described cycle of operation is repeated until the two pointers vibrate in consonance, after which the workman inserts his tweezers or other delicate instrument and bends the free end of the balance-spring 41 sharply upon the upper face of the stud 58, this bend serving to indicate the point at which the spring must be anchored in the clock-mechanism in which the trial-balance unit is ultimately installed. In using the device, it is placed upon a bench or table before the "timer," who looks over it, as it were, into the mirror, in which he sees the two pointers vibrating on a black field, to the exclusion of everything else before him, which enables him to concentrate his attention upon the matter of vital concern at the moment,—namely, the behaviour of the two white-enameded pointers with relation to each other.

By my improvement, I am enabled to time balance-wheels, not only with greater rapidity but with greater accuracy than with any devices of the prior art known to me.

I claim:

1. A device for timing the balance-wheel units of time-pieces, having means for mounting a master balance-wheel unit and a trial balance-wheel unit, and means for directly engaging with the edges of the rims of the balance-wheels of such units for simultaneously starting the two units in oscillation in opposite directions whereby one balance-wheel is given a clockwise impulse and the other an anti-clockwise impulse, the said means comprising yielding impulse-fingers, the edges of which co-act with the edges of the balance-wheel rims.

2. A device for timing the balance-wheel units of time-pieces, having means for mounting a master balance-wheel unit and a trial balance-wheel unit side by side, means for the comparison of their relative action when oscillating, yielding impulse-fingers ar-

ranged to have thrust-engagement with the edges of the rims of such balance-wheels for starting them oscillating in opposite directions, a spring-retracted carrier for such fingers, and means for smartly thrusting the said fingers against the edges of the rims of the said wheels.

3. A device for timing the balance-wheel units of time-pieces, having means for mounting a master balance-wheel unit and a trial balance-wheel unit side by side, means for the comparison of the relative oscillation of the balance-wheels of such units, impulse-fingers having their free ends arranged for thrust-engagement with the edges of the respective balance-wheels for oscillating them in opposite directions, means for smartly moving the edges of the said fingers into engagement with the edges of the said wheels, index-pointers connected with the respective units and arranged in opposition for the convenient observation of their relative movement, and a mirror arranged for the reflection of the said pointers, whereby their relative movement may be noted by the user of the device by their reflection in it.

4. A device for timing the balance-wheel units of time-pieces, comprising front, rear and intermediate frame-plates, means installed in the front and intermediate plates for mounting a master balance-wheel unit and a trial balance-wheel unit, means mounted in the said front and intermediate plates for simultaneously starting the said units in oscillation in opposite directions by direct thrust-engagement with the edges of the rims of their balance-wheels, and means connected with the said units and located in opposition for comparing the speed of their relative oscillations.

5. A device for timing the balance-wheel units of time-pieces, having front, rear and intermediate movement-plates, means located in the front and intermediate plates for the installation of a master balance-wheel unit and a trial balance-wheel unit, means for simultaneously starting said units in oscillation in opposite directions by direct thrust-engagement with the edges of the rims of their balance-wheels, index-pointers connected with the respective units for participating in the movement thereof and located between the intermediate and rear movement-plates, and a mirror located back of the rear plate in position to reflect the relative movement of the said pointers.

6. A device for timing the balance-wheel units of time-pieces, having front, intermediate and rear movement-plates, means located in the front and intermediate plates for the installation of a master balance-wheel unit and a trial balance-wheel unit, means mounted upon the front face of the intermediate movement-plate at a point centrally below the said units for direct thrust-engage-

ment with the edges of the rims of their balance-wheels, whereby the same are simultaneously started oscillating in opposite directions, index-pointers connected with the respective units and located between the intermediate and rear movement-plates for the comparrison of the respective speed of the

units, and a mirror located back of the rear plate for reflecting the action of the said pointers.

In testimony whereof, I have signed this specification.

WILSON E. PORTER.
